UNITED STATES PATENT OFFICE.

PAUL KUPELWIESER, OF BRIONI, NEAR POLA, AUSTRIA-HUNGARY.

SASH-WINDOW.

No. 846,573.

Specification of Letters Patent.

Patented March 12, 1907.

Application filed December 3, 1906. Serial No. 346,102.

To all whom it may concern:

Be it known that I, PAUL KUPELWIESER, a subject of the Emperor of Austria, residing at Brioni, near Pola, in Istria, Austria, have 5 invented certain new and useful Improvements in Sash-Windows, of which the following is a specification.

This invention, which is an improvement on that described in the specification to 10 United States Letters Patent No. 777,347, relates to a sash-window having three sashes adapted to slide vertically in the same vertical plane. The middle sash is always connected with the lower one by pulley-gear, 15 and every time this middle sash is raised it actuates a catch which when the sash is in its highest position holds the upper sash, so that when the middle sash is again lowered it is not followed by the upper sash. The 20 next time the middle sash is raised it again actuates the catch to bring it out of engagement with the upper sash, so that on the subsequent lowering movement both sashes move together. The side rails, which serve 25 to close the joints between the window-sashes and the window-frame, are made to fold back, and each keeps pressed against all the window-sashes by a single actuating device in the several positions of the sashes. For this 30 purpose there is arranged in each side rail a vertically-sliding rod having wedge-shaped surfaces at suitable distances apart and connected with a handle, by turning which the rod may be moved to bring the wedge-shaped 35 surfaces in or out of engagement with hooks on the window-frame, and thus to press the side rails against the sashes or to liberate the rails.

In the accompanying drawings, Figure 1 is 40 an elevation from the inside of a sash-window constructed according to the invention, the sashes being closed. Fig. 1^a is a part longitudinal section showing a detail. Fig. 2 is a vertical cross-section on line A A of Fig. 1. Fig. 3 is a like view to Fig. 1, the middle sash being raised. Fig. 4 is a vertical cross-section 45 on line B B of Fig. 3. Figs. 5 and 6 are sectional views of the upper parts of Figs. 2 and 4, respectively, drawn to an enlarged scale, Fig. 6 being shown partly in elevation. Figs. 7 and 8 are views of a detail in two different positions. Fig. 9 is a horizontal section on line A B of Fig. 8. Figs. 10 and 11 are views showing a detail in two positions. 50 The sash-window comprises three sashes 1,

2, and 3, situated in the same vertical plane and guided laterally in the window-frame 4. The middle sash is the biggest and is moved by hand with aid of a grip 5. It is connected with the lower sash 1 by means of pulley-gear in such a manner that when it is raised the lower sash 1 is lowered into the hollow casing 6, Figs. 3 and 4, and when it is lowered again the lower sash is raised again until the two close together, Figs. 1 and 2. Each pulley-gear consists, preferably, of a nickel band 8, guided over a pulley 7 and connected at one end with the middle sash at 9 and at the other end with the lower sash at 10. The lower sash 1 is preferably connected by 60 hinges 13 with the frame 12, situated in the hollow casing and duly guided therein. Thus when the sash 1 is in the raised position it may be turned on the hinges 13. The frame 12, which is provided with a weight 14, if 65 necessary, insures by its weight the descent of the lower sash 1 when the middle sash 2 is raised.

On an upper and preferably hinged cross-rail 15 of the window-frame 4 there is fixed a 80 catch consisting of a hook 17, pivoted in a casing 16 of the catch. This hook is kept by a spring 18 against a cam 19. This cam is fixed to a ratchet-wheel 20, having four teeth and actuated by a pawl 21, which is 85 pivoted at 22 to a lever 23, which projects below the cross-rail and turns on the pin 24. The pawl 21 has a lateral extension subject to the pressure of the spring 18. In the position of the parts shown in Fig. 10 the hook 90 17 is withdrawn into the casing, resting against the narrower portion of the cam 19.

When the middle sash 2 is raised, a projection 25, which it carries, strikes the lever 23 shortly before the sash is in its highest position. The lever 23 is thus pressed into the casing and the pawl 21 engages with the ratchet 20, turning it through a portion of a revolution, so that the cam 19 is turned to press the hook 17 through a slot 26 in the 100 front wall of the casing 16, in which position it engages in an eye 27, Figs. 2 and 4, carried by the upper sash 3. If now the middle sash 2 be lowered again, the upper sash is left behind, because the hook 17 remains under the 105 influence of the wider portion of the cam 19—that is to say, engaged in the eye 27, Figs. 3, 4, and 6. In this manner a side window-opening is formed. When the middle sash 2 is again raised, the catch is again actuated 110

by the projection 25, so that the hook 17 is again withdrawn into the casing 16, Fig. 10, and the upper sash 3 is free to follow (owing to its weight) the middle sash 2 when this is subsequently lowered. Since the ratchet-wheel 20 possesses four teeth and the cam 19 has the form of a rectangle, the hook 17 is alternately brought in and out of engagement with the upper sash when the lower sash is raised.

For closing the joints between the window-sashes and the window-frame a hinged rail 28 is fixed on the inside of the frame at each side of the window. According to this invention each rail can be pressed against all the window-sashes in whatever position these may be by means of a single handle in order to fasten the sashes in the position in which they happen to be, besides closing the aforesaid joints. For this purpose the arrangement is as follows: On the inside of each rail 28 is a rod 29, suitably guided to slide in the direction of its length. This rod can be raised and lowered by any suitable device actuated by hand—for instance, as here shown, the rod may be connected by a link 31 to an eccentric that can be turned by a handle 30. On the rod 29 are fixed, at suitable distances from each other, wedge-shaped projections 32, and beneath each of these is a slot 33. When the rails 28 are closed against the window-frame 4 and the rods 29 are in their raised positions, Fig. 7, hooks 34, fixed to the window-frame 4, can pass through the said slots. If now the handle 30 is turned upward, Fig. 8, all the wedge-shaped projections 32 engage beneath the noses of the corresponding hooks 34, so that the preferably projecting edges 35 of the rails 28 are firmly pressed against the window-sashes, Fig. 9, and the latter are held in position.

As already stated, the lower window-sash 1 is connected by hinges 13 with the weighted frame 12. This sash when in its upper position can therefore be opened inward after the side rails 28 have been turned back. It may also be arranged that the middle and upper sashes can be opened inward after the side rails have been turned back. For this purpose the middle sash 2 is provided at each side with a fillet 36, guided in the window-frame. This fillet is connected with the sash 2 and extends upward beyond it. Between the upward extensions of these fillets the upper sash 3 is guided. At their lower ends these fillets carry pins 37, which slide in grooves 38, Fig. 1^a, of the window-frame 4. When the sashes 2 and 3 are in their lowest positions, Figs. 1, 1^a, and 2, and the rails 28 have been turned back, the pins 37, turning on the lower ends of the grooves 38, serve as pivots upon which the fillets 36 can be turned inward, carrying with them the sashes 2 and 3.

I claim—

1. A sash-window having a plurality of sashes adapted to slide in the same vertical plane, comprising an upper sash having an eye thereon, an upper cross-rail having a movable catch to engage said eye, operating devices for said catch consisting of a spring normally holding said catch retracted, and means arranged to be actuated by a lower sash in its movements and leave it in inoperative position upon other movements of said lower sash.

2. A sash-window having a plurality of sashes adapted to slide in the same vertical plane, comprising an upper sash having an eye thereon, an upper cross-rail having a movable catch to engage said eye, operating devices for said catch consisting of a spring normally holding said catch retracted, a cam for advancing said catch periodically, and means arranged to be operated by the lower sash in its movement for actuating said cam, whereby said catch is advanced so as to engage said eye upon certain movements of said lower sash and left in retracted position during other movements thereof.

3. A sash-window having a plurality of sashes arranged to slide in an upper sash having an eye thereon, an upper cross-rail having a movable catch to engage said eye, a spring normally holding said catch retracted, a cam for periodically advancing said catch to operative position, a ratchet-wheel to operate said cam, a pivoted pawl to engage said ratchet-wheel, and a projection from said pawl arranged to be engaged by a part on a lower sash in its movement whereby said catch is advanced to engage said eye upon certain movements of said lower sash and left retracted during other movements thereof.

4. A sash-window comprising an upper sash, a lower sash and guiding-frame arranged to slide in the same vertical plane, connections between said upper sash and the frame of said lower sash, whereby upon a movement of said upper sash said lower sash and frame are moved in reverse direction and a hinged connection for said lower sash with said frame.

5. A sash-window comprising a plurality of sashes arranged to slide in the same vertical plane, a movable side rail adapted to be brought over an end of said sashes and means on said rail whereby it is adapted to be brought into engagement with all of said sashes simultaneously.

6. A sash-window comprising a plurality of sashes, arranged to slide in the same vertical plane, a movable side rail adapted to be brought over an end of said sashes, a slidably mounted in said rail carrying wedge members spaced apart and hooks on the window-frame arranged to coöperate with said wedge members whereby said rails may be securely clamped to all of said sashes simultaneously.

7. A sash-window comprising a plurality of sashes arranged to slide in the same vertical plane, hinged side rails adapted to be swung over the ends of said sashes, slidable rods mounted in said rails, wedge members fixed on said rods and spaced apart, and hooks on the window-frame, arranged to co-operate with said wedge members whereby upon manipulation of said rods, said rails 5 may be securely clamped to all of said sashes simultaneously.

8. A sash-window comprising a series of sashes arranged to slide in the same vertical plane, fillets carried by certain of said sashes 15 arranged to be guided in the window-frame, extensions of said fillets adapted to guide an upper sash and pins carried by said fillets arranged to slide in grooves of the window-frame and to fulcrum in the bottoms of such 20 grooves whereby certain of said sashes may be swung laterally upon said pins as pivots.

9. A sash-window comprising a series of sashes arranged to slide in the same vertical plane, means for detachably holding the upper sash of said series in elevated position, 25 means co-operating with an intermediate sash in certain of its movements arranged to render inoperative said holding means for the upper sash and permitting same to remain operative during other movements, a lower 30 sash and connections between the same and said intermediate sash whereby movements of the latter occasion movements of the former in reverse direction.

In testimony whereof I have hereunto set 35 my hand in presence of two subscribing witnesses.

PAUL KUPELWIESER.
